SKI REPAIR KIT

William S. Moody, Cranston, R. I., assignor to Moody Machine Products Co., Inc., a corporation of Rhode Island

Application February 8, 1954, Serial No. 28,912

Term of patent 3½ years

(Cl. D93—4)

Fig. 1.

Fig. 2.

Fig. 3.

Fig. 4.

Figure 1 is an elevational view of a ski repair kit showing my new design;

Figure 2 is an exploded view;

Figure 3 is a top end view; and

Figure 4 is a bottom end view thereof.

I claim:

The ornamental design for a ski repair kit, substantially as shown.
